(57) **CLAIM**

The ornamental design for an infrared thermometer, as shown and described.

DESCRIPTION

FIG. 1 is a top rear left side perspective view of an infrared thermometer having the inventive design;

FIG. 2 is a bottom front right side perspective view of the infrared thermometer shown in FIG. 1;

FIG. 3 is a bottom rear left side perspective view of the infrared thermometer shown in FIG. 1;

FIG. 4 is a bottom orthogonal view of the infrared thermometer shown in FIG. 1;

FIG. 5 is a top orthogonal view of the infrared thermometer shown in FIG. 1;

FIG. 6 is a front orthogonal view of the infrared thermometer shown in FIG. 1;

FIG. 7 is a rear orthogonal view of the infrared thermometer shown in FIG. 1;

FIG. 8 is a top front left side perspective view of the infrared thermometer shown in FIG. 1;

FIG. 9 is a left side orthogonal view of the infrared thermometer shown in FIG. 1; and,

FIG. 10 is a right side orthogonal view of the infrared thermometer shown in FIG. 1.

The broken line showing of structural features is included for the purpose of illustrating non-claimed subject matter and forms no part of the claimed design.
